FIG. 17 is a rear view of the shorts shown in FIG. 16;

FIG. 18 is a right side view of the shorts shown in FIG. 16;

FIG. 19 is a front view of shorts showing a seventh embodiment of the design;

FIG. 20 is a rear view of the shorts shown in FIG. 19;

FIG. 21 is a right side view of the shorts shown in FIG. 19;

FIG. 22 is a front view of shorts, showing a second embodiment;

FIG. 23 is a rear view thereof; and,

FIG. 24 is a right side view thereof.

FIG. 25 is a front view of shorts showing a ninth embodiment of the design;

FIG. 26 is a rear view of the shorts shown in FIG. 25;

FIG. 27 is a right side view of the shorts shown in FIG. 25;

FIG. 28 is a front view of shorts showing a tenth embodiment of the design;

FIG. 29 is a rear view of the shorts shown in FIG. 28;

FIG. 30 is a right side view of the shorts shown in FIG. 28;

FIG. 31 is a front view of shorts, showing a eleventh embodiment of a new design;

FIG. 32 is a rear view of the shorts shown in FIG. 31;

FIG. 33 is a right side view of the shorts shown in FIG. 31;

FIG. 34 is a front view of shorts showing a twelfth embodiment of the design;

FIG. 35 is a rear view of the shorts shown in FIG. 34;

FIG. 36 is a right side view of the shorts shown in FIG. 34;

FIG. 37 is a front view of shorts showing a thirteenth embodiment of the design;

FIG. 38 is a rear view of the shorts shown in FIG. 37;

FIG. 39 is a right side view of the shorts shown in FIG. 37;

FIG. 40 is a front view of shorts showing a fourteenth embodiment of the design;

FIG. 41 is a rear view of the shorts shown in FIG. 40;

FIG. 42 is a right side view of the shorts shown in FIG. 40;

FIG. 43 is a front view of shorts showing a fifteenth embodiment of the design;

FIG. 44 is a rear view of the shorts shown in FIG. 43;

FIG. 45 is a right side view of the shorts shown in FIG. 43;

FIG. 46 is a front view of shorts showing a sixteenth embodiment of the design;

FIG. 47 is a rear view of the shorts shown in FIG. 46;

FIG. 48 is a right side view of the shorts shown in FIG. 46;

FIG. 49 is a front view of shorts showing a seventeenth embodiment of the design;

FIG. 50 is a rear view of the shorts shown in FIG. 49;

FIG. 51 is a right side view of the shorts shown in FIG. 49;

FIG. 52 is a front view of shorts showing an eighteenth embodiment of the design;

FIG. 53 is a rear view of the shorts shown in FIG. 52;

FIG. 54 is a right side view of the shorts shown in FIG. 52;

FIG. 55 is a front view of shorts showing a nineteenth embodiment of the design;

FIG. 56 is a rear view of the shorts shown in FIG. 55;

FIG. 57 is a right side view of the shorts shown in FIG. 55;

FIG. 58 is a front view of shorts showing a twentieth embodiment of the design;

FIG. 59 is a rear view of the shorts shown in FIG. 58; and,

FIG. 60 is a right side view of the shorts shown in FIG. 58. The figures illustrate the shorts in a state in which the shorts are worn by a wearer.

The left side of the shorts is a mirror image of the right side of the shorts.

The broken lines represent the portions of the shorts that form no part of the claimed design. The cross-hatching indicates contrast in material and/or color with portions of the shorts that are not cross-hatched, and no particular color is claimed. The solid black shading indicates color contrast with non-shaded portions of the shorts, and no particular color is claimed.
